UNITED STATES PATENT OFFICE

RICHARD KAIER, OF CRANFORD, NEW JERSEY, ASSIGNOR TO THE SINGER MANUFACTURING COMPANY, OF ELIZABETH, NEW JERSEY, A CORPORATION OF NEW JERSEY

SHEET-METAL BELT-CONVEYER FOR HEAT-TREATING FURNACES

Application filed May 27, 1931. Serial No. 540,335.

This invention relates to a belt for conveying work through a heat-treating furnace and particularly to an endless belt for continuously conveying work-pieces buried in a thin layer of carburizing material through a furnace for the carburization of such work-pieces, as disclosed in the U. S. patent to Willard and Kaier, No. 1,792,456, of Feb. 10, 1931.

10 The invention has for an object to provide a strong, durable and inexpensive conveyer-belt for the work in question which is resistant to distortion and will retain its ability to run freely around the pulleys of the conveyer system without stiffening under the action of the heat and pulverized carburizing material or other conditions to which it is subjected in use.

20 The invention comprises the devices, combinations and arrangements of parts herein-after described and claimed.

The features of the invention and the advantages attained thereby will be readily understood by those skilled in the art from 25 the following detailed description of a preferred embodiment thereof illustrated in the accompanying drawing in which Fig. 1 is a top plan view of a sheet-metal belt-conveyer embodying the invention; the sections of the 30 conveyer being in their initially assembled relation to one another. Fig. 2 is a section on the line 2—2, of Fig. 1. Fig. 3 is a top plan view of the conveyer with the sections in the working relation they assume relative to 35 one another after the conveyer has been put to use, and Fig. 4 is a section on the line 4—4, of Fig. 3.

The belt-conveyer illustrated comprises a series of sheet-metal sections 1 disposed in 40 edge-to-edge relation; the adjoining edges of the sections extending widthwise or transversely of the belt. The sections 1 are perforated at 2 along their adjoining edges and wire edge-connectors in the form of coils 3 45 are threaded through the perforations 2, as

shown in Figs. 1 and 2, to connect the sections of the belt together. Embraced within each coil 3 is a reinforcing member or rod 4 which is thicker than the sheet-metal sections 1 and is preferably welded at 5 to the adjacent 50 edge of one of the sheet-metal sections within the coil 3. The welds 5 need not be continuous widthwise of the belt but may be formed at spaced spots such, for example, as at the ends and center of the rods 4.

To facilitate manufacture of the belt, the coils 3 are preferably initially made of true spiral form so that they may be readily threaded through the perforations 2 by rotation of such coils about their axes; the edge 55 of one sheet-metal section overlapping the reinforcing rod 4 of the adjoining section. The ends of the coils 3 are preferably anchored at 3' to prevent loosening of such ends. After the belt has been subjected to use in a furnace, the lengthwise strain to which the belt is subjected tends to flatten the coils 3 to the oval form shown in Fig. 4. If it were not for the relatively thick reinforcing rods 4, the flattening or collapse of 70 the coils 3 would continue until they engaged the upper and lower surfaces of sections 1 and thus destroyed the flexibility of the hinge-connections. The relatively thick reinforcing rods 4 within the coils 3 prevent 75 collapse of such coils beyond the form shown in Fig. 4 and maintain a suitable space between the upper and lower convolutions of such coils for a free hinge action of the sheet-metal sections, as indicated in dotted 80 lines at the right-hand end of Figs. 2 and 4. As belt-conveyers of this type are usually made in endless form and are required to run over pulleys, it is important that the 85 flexibility of the hinge-connections be maintained under the working conditions to which the belt is subjected. Otherwise, premature distortion and failure of the belt will occur due to the stiffening of the hinge-connections.

The present belt is particularly adapted for use in continuous case-hardening furnaces of the type illustrated in said Willard and Kaier patent, wherein the belt-conveyer must carry not only the work-pieces but also a thin layer of pulverized carburizing material in which the work-pieces are buried.

Having thus set forth the nature of the invention, what I claim herein is:—

1. A belt-tension transmitting hinge connection for adjoining sections of a sheet-metal belt-conveyer comprising, a pair of sheet-metal belt-sections perforated along their adjacent edges and arranged initially with their edges overlapping, a true cylindrical spiral wire coil threaded through the perforations of said overlapping edges, and a reinforcing rod secured to one of said sections, said rod being thicker than said belt-sections and disposed within said coil, the diameter of said coil being initially great enough to permit said sections to be pulled apart under the working tension on the belt sufficiently to permit the initially overlapping edges to be drawn into the same plane and out of overlapping relation.

2. A conveyer-belt comprising a plurality of sheet-metal belt-tension-transmitting sections arranged in edge-to-edge relation, said sections having series of apertures spaced inwardly from their adjoining edges, wire edge-connectors passing through said apertures over and under said adjoining edges, and a reinforcing strip welded to one edge of each section and adjoining the non-reinforced edge of an adjacent section, said strips being embraced within the respective wire edge-connectors, said wire edge-connectors being initially formed as true cylindrical spirals connecting said adjoining edges in overlapping relation, the diameter of the cylindrical spirals being great enough to permit sufficient deformation under the working tension on the belt-sections to draw the overlapping edge-portions into edge-to-edge abutting relation.

3. A belt-tension transmitting hinge-connection for adjoining sections of a sheet-metal belt-conveyer comprising a pair of sheet-metal belt-sections having overlapping edge-portions, said sections having series of perforations adjacent said overlapping edge-portions, and a true cylindrical spiral wire coil threaded through said perforations, the diameter of said coil being initially great enough to permit said sections to be pulled apart under the working tension on the belt sufficiently to permit the initially overlapping edges to be drawn down into the same plane and out of overlapping relation.

4. A belt-tension transmitting hinge-connection for adjoining sections of a sheet-metal belt-conveyer comprising a pair of sheet-metal belt-sections having overlapping edge-portions, said sections having series of

perforations adjacent said overlapping edge-portions, a true cylindrical spiral wire coil threaded through said perforations, and means for stiffening the free edge of one of said overlapping edge-portions, the diameter of said coil being initially great enough to permit said sections to be pulled apart under the working tension on the belt sufficiently to permit the initially overlapping edges to be drawn down into the same plane and out of overlapping relation.

In testimony whereof I have signed my name to this specification.

RICHARD KAIER.
